(57) **CLAIM**

The ornamental design for an electronic cigarette, as shown and described.

DESCRIPTION

1. Electronic cigarette

1.1 : Perspective

1.2 : Perspective

1.3 : Front

1.4 : Back

1.5 : Left

1.6 : Right

1.7 : Top

1.8 : Bottom

The present design relates to an electronic cigarette; reproductions 1.1 to 1.8 are respectively front, top perspective, rear, bottom perspective, front, rear, left side, right side, top, and bottom views of the electronic cigarette.

The broken lines in the drawings depict portions of the electronic cigarette that form no part of the claimed design.

1 Claim, 8 Drawing Sheets
